UNITED STATES PATENT OFFICE

KARL SCHAFFNER, OF NUERMBERG, GERMANY, ASSIGNOR TO THE FIRM VEREINIGTE SCHUHFABRIKEN BERNEIS-WESELS A. G., OF AUGSBURG-OBERHAUSEN, GERMANY

DESIGN FOR A BABY'S SHOE

Application filed July 8, 1929, Serial No. 31,961, and in Germany April 10, 1929. Term of patent 3½ years.

To all whom it may concern:

Be it known that I, KARL SCHAFFNER, a citizen of the German Republic, resident of No. 154 Fallrohrstrasse, Nuremberg, Germany, have invented a new, original, and ornamental Design for a Baby's Shoe, of which the following is a specification, reference being had to the accompanying drawing, forming part thereof.

The figure is a front perspective view of a baby's shoe showing my new design.

I claim:

The ornamental design for a baby's shoe, as shown.

KARL SCHAFFNER.
